DRIVING MEANS FOR DETECTOR ROLLS IN
GRADING MACHINESCharles C. Thomas, Medford, Mass., assignor to
Lacene Manufacturing Corporation, Lawrence,
Mass., a corporation of New Hampshire

Application July 3, 1947, Serial No. 758,743

6 Claims. (Cl. 101—43)

1

My present invention relates to grading machines of the kind which grade died-out blanks of leather such as soles, taps, heel lifts, counters or other blanks, in accordance with the thickness of the thinnest spot as determined by a detector roll. More particularly my present invention relates to improved driving means between the main drive and the detector roll being an improvement over the Letters Patent No. 1,820,010 granted to Cogswell August 25, 1931.

The principal object of my present invention is to produce an improved drive for the gauge or detector roll;

Another object is to provide an improved drive for the detector roll which reduces the friction on the driving gears and between the leather sole blanks and the rolls and at the same time reduces the load on the machine thereby increasing the efficiency and accuracy of the grading operation, and

Other objects and novel features will be apparent as the description of the same progresses.

Referring more in detail to the drawings,

Fig. 1 is a fragmentary cross-section and end elevation of the grading machine as viewed in the area of the detector roll and drive roll gears;

Fig. 2 is a diagrammatic fragmentary cross-section of the driving gears, as set forth in the Cogswell Patent No. 1,820,010 showing the previous means of compensating for differences in the speeds of the two gear shafts;

Fig. 3 is a similar diagrammatic fragmentary cross-section of the driving gears as set forth in the Cogswell Patent No. 1,820,010 showing the lag in the movement of the lower gear with respect to that of its shaft during the passage of a blank between the rolls;

Fig. 4 is a diagrammatic fragmentary cross-section taken on line 4—4 of Fig. 1 showing my improved means for compensating for the lag in the movement of the lower or detector roll gear with respect to that of its shaft during the passage of a blank between the rolls;

Fig. 5 is a fragmentary cross-section similar to Fig. 4 but showing a different position of the gears etc. during the passage of the blank between the rolls;

Fig. 6 is another fragmentary cross-section similar to Fig. 4 but showing a still different position of the lower gauge or detector roll gear and shaft, and also showing the shoe sole blank in dot-and-dash lines passing between the rolls,

Fig. 7 is still another fragmentary cross-section similar to Fig. 4 but showing another position of the detector roll gear and shaft, the shoe sole

2

blank having passed completely through the rolls.

Referring to the drawings and particularly to Fig. 1, the upper gauge roll 10 is journaled in the bearings 11 and 12. These bearings are fixed to the frame of the machine a portion of which is indicated at 13. Power to operate the gauge rolls is derived from the shaft 14 and thence is transmitted to the detector gauge roll 15 by means of the gears 16, 17 and 18 and 19 at such times when there is no shoe sole blank passing between the upper gauge roll 10 and the lower detector gauge roll 15. When there is a shoe sole blank passing between the rolls 10 and 15 the shoe sole blank drives the roll 15 and the gears 16, 17, and 18 and 19 are ineffective as driving or driven members. This feature will be more fully discussed further along in the specification.

The upper gauge roll 10 is fixed to the drive shaft 14 and the lower detector gauge roll 15 is fixed to the shaft 15a. Bearings 20 and 21 are movable vertically in the frame of the machine and the roll 15 is maintained in a predetermined high position, except when depressed by a sole blank, by means of the levers 22 and 23. In effect the roll 15 and shaft 15a are free floating at all times and may tilt out of parallel relation with roll 10 when influenced by a sole blank in passage between the two rolls. This is well known construction, as shown in Cogswell 1,726,610 issued September 3, 1929, et al.

Prior to August 25, 1931, as set forth in Cogswell No. 1,820,010, it had been the practice to make the feeding and detecting rolls 10 and 15 of the same diameter, as best illustrated in earlier patents to Nichols and well known in the art. Such rolls were usually connected by means of ordinary spur gears of standard involute shape with teeth of sufficient length to remain intermeshed at all times during the movement of separation of the feeding and detecting rolls, whereby the lower or detector gauge roll was positively driven through said gearing by the upper or fixed roll which is driven from the main drive shaft 14. By reason of the constant relative movement between the gears of the two sets during the detecting operation of the machine as the yielding roll moves up and down, there is a constant rubbing engagement between the teeth of the two sets of gears which results in friction, wear, and undesirable resistance in the movements of the yielding roll due to the meshing of the gears.

When gauge rolls of the same diameter are used as in older machines it is quite apparent that when a shoe sole blank is passed through the rolls, the driving or upper gauge roll has auto-

matically been increased in diameter because of the thickness of the blank which is in direct pressure contact with the lower roll 15, therefore the gear ratio changes and the angular speed of the lower roll is greater than the upper driving roll. Because of this condition the gear teeth having a one to one ratio begin to jam. The only relief under such conditions is slippage of the blank on the lower roll which increases the load on the machine and effects the quality of the grading.

In Cogswell No. 1,820,010, dated August 25, 1931, an attempt was made to correct this difficulty and to provide a construction in which the lower yielding roll was driven by the upper roll through gearing in the usual way when no blank was between the rolls, but in which the instant a blank entered between the rolls the gears were automatically disengaged one from the other and remained disengaged to rotate out of contact with one another during the passage of the blank between the rolls, the lower yielding roll being rotated as an idler roll by direct frictional contact with the passing blank. Due to the fact that it is impossible to establish dimensions so that a machine will operate equally well on all of the various lengths and thicknesses of blanks which must be graded, the difference in fixed diameters of the gauge rolls taken alone does not work out satisfactorily.

Figs. 2 and 3 illustrate the means used in the Cogswell Patent No. 1,820,010 designed to correct the difficulty. Rolls 25 and 26 are fixed to respective shafts 25a and 26a. It will be noted that roll 26 is smaller in diameter than roll 25. Gears 27 and 28 are fixed to the shafts 25a and 26a. When the sole blank B is passing between the rolls 25 and 26, the lower roll 26 is caused to rotate at an angular speed slightly faster than roll 25. The spur gears 27 and 28 instead of being of ordinary conventional form of gears are specially shaped, as illustrated in Figs. 2 and 3. The front or active faces 29 of the upper or driving gear teeth, considered with reference to the direction of rotation of the gears as indicated by the arrows, are of conventional form and engage the rear or active faces 30 of the lower gear 28 which are also of conventional form, to drive the lower roll 26 in the usual way when no blank is between the rolls 25 and 26. The rear or inactive faces 31 and 32 of the respective gears 27 and 28 are cut away or mutilated in order to provide spaces or clearances between the teeth at that side.

Before and at the time when the blank B is presented to the feeding and detecting rolls, the teeth of each pair of gears are in intermeshed engagement and the gear 28 is being driven by the gear 27 in the usual way, but as soon as the forward end of the blank B has entered between the two rolls, the blank is carried forward by the upper roll 25 alone, the slightly smaller roll 26 turning over with the movement of the blank B but at a slightly greater angular speed than the roll 25. Fig. 2 shows the position of the gears before the blank B enters between the rolls or at the instant when the blank enters the nip of the roll. Fig. 3 shows the approximate position of the gears when the blank B is partially through the rolls. From the instant the blank B enters between the rolls the teeth of gear 28 will be moved ahead of the teeth of the gear 27 by reason of the slightly greater speed of the smaller roll 26, so that there will be no engagement between the teeth of the gears 27 and 28 during the pas-

sage of the blank between the feeding roll 25 and the detecting roll 26. This leaves the lower detecting roll 26 free to follow the irregularities of the blank B without any resistance from the meshing of the gears immediately after the blank enters the rolls.

This earlier improvement works successfully for certain size and type blanks. Unfortunately it is impossible to establish standard dimensions of the parts so that the mechanism described will operate equally well on all the various lengths and thicknesses of blanks which must be graded. If the ratio of the roll diameters is too nearly unity, the advantage of the device will be lost, because on short blanks the gears may never get a chance to move out of contact. On the other hand, if the ratio is much greater than unity, the lower roll will turn so much faster than the upper roll that the mutilated side of the succeeding tooth may overtake the tooth of the upper gear before the blank is graded. This is most apt to occur on the longer or thinner blanks. If this takes place when the blank still has some distance to travel in the rolls, jamming is bound to occur. The gear teeth are then forced together with extreme pressure. This situation can only be relieved by the occurrence of slippage between the roll and the leather blank. The adverse effect of this occurrence upon accurate grading is apparent not to mention the greatly increased load on the machine at this stage and frictional wear on the gear teeth as evidenced by an inspection of machines which have been in service for some time. The mutilated faces of the gear teeth which supposedly never come into contact actually show much wear.

In my present invention I have obviated this condition. In the Cogswell Patent 1,820,010, the difference in angular rotation of the two rolls is limited to approximately six degrees by the dimension of the gears. In my improved device using the same size gears the difference in angular rotation is thirty times or more as great. Because of this result it is permissible to increase the difference in the diameters of the two gauge rolls materially. This result makes the action more positive, and insures the freedom of movement of the lower roll without any interference whatsoever between the gears. In the present invention as shown in Figs. 4 to 7 inclusive, as in the said Cogswell patent, the upper gauge roll 10 is made with a diameter greater than the lower detector roll 15 but the difference in diameter of these two rolls is very much more pronounced. In my improved device the gear teeth are of the wringer type and are not mutilated. The lower gauge roll gear 18, instead of being attached rigidly to the shaft 15a, is rotatable on the shaft for a limited angular rotation of over one hundred and eighty degrees. The roll 10 is fixed to the shaft 14 which is a positive drive shaft. The teeth of gear 18 are always in mesh with the teeth of the gear 19.

Referring more specifically to the improvement as set forth in Figs. 4 to 7 inclusive, Fig. 4 shows the upper gauge roll gear 18 meshed with the lower detector roll gear 19 rotating in the direction of the arrows. A sole blank A is travelling across the table T from right to left and about to enter between the rolls 10 and 15. In this position attention is directed to the gear 19 upon the side of which is fixed a stop member 35. While no blank is being passed between the rolls 10 and 15 the shaft 15a is driven only by the gear 19 from gear 18, but only when the stop mem-

ember 35 which is attached to the gear 19 is in engagement with the key member 36 fixed to the shaft 15a by means of the machine screw 37. This is the position shown in Fig. 4. In this position the shaft 15a is an idling shaft and being driven by the gear 19. When the blank A enters the bite area of the roll 10 the drive of the shaft 15a automatically shifts from the gear 19 to the roll 10 the radius being the lower side of the sole blank A. As pointed out previously there is a marked difference in the diameters of roll 10 and roll 15, roll 15 being somewhat smaller in diameter than roll 10 consequently the angular speed of roll 15 is materially increased with respect to roll 10. The speed of gears 18 and 19 remain constant but the speed of the detector roll gear shaft 15a has been increased over the roll 10 therefore the shaft 10 and the key member 36 immediately pull away from the stop member 35 fixed on the gear 19. This effect which is slightly magnified for the sake of clarity is illustrated in Fig. 5 in which the blank A has progressed to a certain point through the rolls 10 and 15. In this figure it will be noted that the bottom of the sole blank A which is now the driver of roll 15 has pulled the key 36 away from the gear stop 35 and is independently driving the roll 15 and shaft 10, and at this point the gear 19 is merely idling on the shaft 10, there being no load on the gear 18. Then the gear 19, together with the shaft 15a, is free to rise and fall with respect to the gear 18 without any appreciable friction or back-lash being present in the machine. Fig. 6 illustrates another more advanced position of the passage of the blank A through the rolls 10 and 15 in which the gears 18 and 19 are in mesh but not carrying any load, and in which the detector roll shaft 15a has drawn farther away from the engagement with the gear 18 as shown in Fig. 4. In Fig. 7 the sole blank A has passed through the rolls 10 and 15 and the detector roll 15 is no longer being driven by the upper gauge roll 10. At this particular point the detector roll 15 is at rest and not rotating; however, this is for a very short interval of time. As previously stated the upper roll 10 is continuously driven by means of the main drive shaft 14, and as the gear 18 is fixed to the shaft 14 it also is in continuous rotation. The gear 19 being in direct mesh with the gear 18 continues to rotate on the detector roll shaft 15a until interrupted. This occurs when the gear stop member 35 catches up with the key member 36 fixed in the shaft 15a of the detector roll 15. In Fig. 7 I have illustrated the position of the driving and driven elements during the interval between the exit of one blank and the time of presentation of the next blank to the rolls, as shown in Fig. 4. Referring back to Fig. 7 the shaft 15a is not now rotating but the gear 19 is rotating continuously and the stop member 35 is approaching the key 36 of shaft 15a, as indicated by the arrows. When the stop member 35 engages the key 36 of shaft 15a the shaft 15a will rotate to approximately that position shown in Fig. 4. The exact position of the key 36 on the shaft 15a and the stop member 35 on the gear 19 as shown in the drawing may vary in actual practice, the positions shown being illustrative only. Also any type of gear tooth may be substituted for the wringer type shown in the drawings. I prefer the wringer type tooth for certain reasons but the device is not limited to any one type.

My present invention differs considerably over the said Cogswell improvement in that the lower

detector roll gear 19 operates at all times at the same angular speed as the upper gauge roll gear 18 there being no lost motion between the two gears while the lower detector roll shaft 15a operates only when a sole blank is between the rolls or when the stop member 35 is in engagement with the key 36 on the shaft 15a as shown in Fig. 4.

Other means may be substituted for the specific key in the shaft 15a or the specific stop 35 on the gear 19, or the key 36 on the shaft 15a may vary in angular dimension or the stop member 35 on the gear 19 may be much wider in angular dimension. In fact, the device may be modified in actual practice and proportions altered within wide limits while still remaining within the spirit of the appended claims the drawings being illustrative only and not limiting.

Having thus described my invention what I claim as new is:

1. In a machine for grading shoe sole blanks, a gauge roll driving shaft, a gauge roll fast on the driving shaft, a driving gear fixed to the driving shaft at one side of the gauge roll, a second shaft yieldably supported in spaced relation to the driving shaft, a detector roll of smaller diameter than the gauge roll fixed to the second shaft, a driven gear rotatably mounted on the second shaft in position to mesh with the driving gear, a pair of cooperating stop elements located between the detector roll and the driven gear for operatively connecting these members together, one of the stop elements being free to move ahead of the remaining stop element in response to an increase in speed of rotation of the detector roll over that of the gauge roll.

2. In a machine for grading shoe sole blanks a gauge roll driving shaft having a driving gear fixed thereon, a gauge roll fast on the shaft at one side of the driving gear, a second shaft yieldably supported in spaced relation to the driving shaft, a driven gear mounted on the second shaft in a position to mesh with the driving gear, said driven gear being rotatable on its shaft, a stop member on said shaft, a second stop member located on the driven gear in a position to engage with the stop member on the shaft and limit rotative movement of the driven gear thereon, a detector roll mounted on the second shaft in close proximity to the gauge roll, the detector roll being relatively smaller in diameter than the gauge roll and adapted to move relative to the driven gear at speeds which vary in accordance with the speed of the gauge roll thereby to relieve stress between the driving gear and the driven gear when the detector roll engages a shoe sole blank.

3. In a machine for grading shoe sole blanks, a drive shaft having a gauge roll and a driven gear fixed thereon, a second driven shaft yieldably supported in spaced relation to the drive shaft, a detector roll of smaller diameter than the gauge roll, mounted on the second shaft, in close proximity to gauge roll and arranged to rotate at speeds which vary in accordance with the speeds of the gauge roll, a driven gear rotatably mounted on the second shaft, stop means for operatively connecting the detector roll with the driven gear, said stop means including an abutment on the driven gear and a stop element movable with the detector roll from a position of contact with one side of the abutment member to a position of contact with an opposite side thereof, said driven gear operating to intermittently transfer power from the driving shaft to the driven shaft in re-

sponse to change in position of the detector roll and shaft relative to the driven gear.

4. In a machine for grading shoe sole blanks, an upper gauge roll fixed on a drive shaft member, a relatively smaller detector roll mounted on a second shaft which is yieldably supported in spaced relation to the first drive shaft member, a fixed gear on the drive shaft in mesh with a rotatable gear on the second shaft, stop means for operatively connecting the rotatable gear to its respective shaft, said stop means including an abutment on the rotatable gear and a second stop element movable with the detector roll away from the abutment said gear means operating to intermittently transfer power from the driving shaft to the driven shaft in response to change in position of the detector roll on its respective shaft.

5. In a machine for grading shoe sole blanks a gauge roll driving shaft, a gauge roll fast on the driving shaft, a driving gear fixed to the driving shaft at one side of the gauge roll, a second shaft yieldably supported in spaced relation to the driving shaft, a driven gear rotatably mounted on the second shaft in position to mesh with the driving gear, a detector roll, of smaller diameter than the gauge roll, located on the second shaft and normally adapted to lie in close proximity to the gauge roll, and cooperating stop means located between the detector roll and the driven gear and so constructed and arranged as to permit limited relative movement between the driven roll and the driven gear for the purpose of relieving friction between the driving gear and driven gear when a blank is passed between the rolls.

6. In a machine for grading shoe sole blanks, a gauge roll driving shaft, a gauge roll fast on the driving shaft, a driving gear fixed to the driving shaft at one side of the gauge roll, a second shaft yieldably supported in spaced relation to the driving shaft, a detector roll, of smaller diameter than the gauge roll, fixed to the second shaft, a driven gear rotatably mounted on the second shaft in position to mesh with the driving gear, stop means for limiting rotation of the driven gear on the second shaft, the stop means including an abutment projecting radially outward from said second shaft, and a second abutment projecting axially outward from a side of the driven gear into the path of movement of the first abutment.
